TILTING CUSHION STRUCTURE

Kenneth K. Horner, Chicago, and Laurence W. Hiltman, Palos Heights, Ill., assignors to S. Karpen & Bros., Chicago, Ill., a corporation of Illinois

Application January 19, 1946, Serial No. 642,308

2 Claims. (Cl. 155—120)

1

This invention relates to a tilting cushion structure for bus, railway, and other types of seats to which the invention is applicable.

An object of the invention is to provide means for permitting the ready tilting of a seat by merely raising the back portion of the seat to the desired point. A further object is to provide means for tilting a seat cushion whereby the latching means for elevating it in stepped positions may be rendered inoperative to restore the cushion to its initial position and the latching means to its operative position. Yet another object is to provide a cushion and back structure with cooperating means whereby guide and link means limit the angular separation of the cushion and back, while at the same time providing means for supporting the rear portion of the cushion at desired points of elevation. Other specific objects and advantages will appear as the specification proceeds.

The invention is illustrated, in a preferred embodiment, by the accompanying drawing, in which—

Figure 1 is a side view in elevation of a seat equipped with structures embodying our invention; Fig. 2, a broken vertical sectional view of tilting mechanism embodying our invention; Fig. 3, a view similar to Fig. 2 but showing the mechanism at the upper limit of its movement; Fig. 4, a view similar to Fig. 3 but showing the tilting mechanism in a releasing stage near the lower limit of its movement; and Fig. 5, a top plan view taken at line 5—5 of Fig. 2.

In the illustration given, A designates a seat base; B, a frame carried thereby; C, a back carried by the frame B; and D, a cushion carried by frame B.

The seat structure may be of any suitable type or construction. In the illustration given, A designates a base of the usual type carrying a frame structure B. The frame structure B may be of any suitable material or of construction. It may be permanently anchored upon the base A or mounted thereon for a turning movement through an angle of 180° or more. Since such structures are well known, a detailed description is believed unnecessary.

Supported upon frame B is a back C, which also may be of any suitable materials or form of construction. The present invention may be employed with any type of seat back.

The cushion D may be of the usual type or of any suitable type. It ordinarily consists of a core member formed of springs or a porous rubber body, hair, etc., mounted upon a frame structure and covered by a fabric body. It will be under-

stood that any type of seat may be employed with the present invention.

In the illustration given, the seat back C is provided with a bracket member 10 which is provided with inwardly-extending flanges 11, as shown more clearly in Fig. 5. The lower ends of flanges 11 are provided with pins 12 connecting the flanges to a guide link 13 having an arcuate slot 14 therein. The plate 10 is provided with a plurality of recesses 15 which may extend partly or entirely through the plate. In the illustration given, the recesses 15 are formed by cutting away spaced portions of the plate.

The upper end of the bracket member 10 is provided with an inwardly-extending shoulder 16, and the lower portion of bracket 10 is provided with an inwardly-extending release arm 17.

The cushion D is provided with a frame member 18 to which is secured a bracket 19 by means of rivets 20. The bracket member 19 is provided with integral depending side members 21 perforated at their rear to receive a pin 22 which extends also through the arcuate slots 14 of the members 13. The side walls are connected at their upper side by an integral web 23 through which the rivets 20 extend.

At the forward end of the side flanges 21 of bracket 19 is a pivot pin 24 which secures a latch member 25 between the side walls 21. The latch member 25 is provided with a downwardly-inclined central web 26 adapted to engage the recesses 15 of bracket 10, and is also provided with a latching recess 27 in the rear portion thereof.

A spring member 28 is secured to the web 23 of bracket 19 by rivets 29, and is equipped with a downwardly- and forwardly-extending portion 30 terminating in a nose 31.

The cushion D may be pivotally secured at its forward end upon the supporting frame B, as indicated in Fig. 1. In raising the cushion, the rear portion of the cushion D is grasped by the hands and raised to effect the elevation of the rear portion of the structure D. It is not necessary for the occupant to vacate the chair while making the adjustment. He may merely draw the rear portion of the structure D upwardly while still sitting on the cushion, as will be described in greater detail hereinafter.

50

Operation
In the operation of the structure, assuming that the cushion is in its lowermost position, the operator merely raises the rear portion of the cushion, and the latch 25, which is normally urged outwardly toward the bracket 10, as shown

more clearly in Fig. 2, slips into one of the recesses 15. The cushion will be supported in the above position by the parts as described. If it is desired to raise the cushion still further, the operator merely raises up the back portion of the cushion still further, and the forward cam face of the latch member 25 pushes the member 25 rearwardly until another recess 15 is reached, at which point the member 25, under the pressure of spring 28, swings into the newly reached recess. By this means, the cushion can be raised through the series of spaced openings with which the bracket 10 is provided, and it will be understood that the bracket 10 may have any desired number of recesses 15.

When it is desired to restore the cushion to a lower position, it is merely necessary to raise the cushion to the upper limit of its movement, as shown best in Fig. 3. Here, the shoulder 16 engages the latch member 25 and forces it downwardly until the cam head 31 of the spring engages the recess 27 of latch member 25. By this means, the latch member 25 is held in retracted position, and the cushion may be freely moved downward to its initial position.

When the cushion nears its initial position, the latch member 25 engages the releasing shoulder or arm 17 of bracket 10, and the member 25 is swung outwardly and away from the spring 28 so that the cam head 31 is released from the recess 27 of member 25. The cam head 31 of spring 28 then resumes its position, as shown in Fig. 2, and urges the member 25 forwardly into operative latching position.

In all of the foregoing movements, the cushion is guided in its tilting operation by the links 13 carried by the side flanges 11 of bracket 10 and by the engagement with the arcuate slots of member 13 with the pin 22. Pin 22 is rendered rigid and effective as a guide means by reason of its support within the side walls 21 of the cushion bracket 10. At the same time, the lower shoulder 17, as well as the seat structure B, serves as a stop for the downward movement of cushion D.

The structure described is effective with a cushion which has heretofore been regarded as substantially non-tiltable because of its loose position upon a seat base. The new structure provides the necessary rigidity and guide structure, while at the same time providing the necessary tilting action. To operate the structure, it is never necessary for the user to remove the cushion or to attempt to reach the latch mechanism described, the only operation being that of merely raising or depressing the cushion to achieve the results set out.

While in the foregoing specification, we have

set forth considerable details as illustrative of one mode of using the invention, it will be understood that such details may be varied widely by those skilled in the art without departing from the spirit of our invention.

We claim:

1. In a seat structure, a cushion carried thereby, a back equipped with a plate having a plurality of spaced recesses therein, said plate having an upper shoulder and lower shoulder, a bracket carried at the back of the cushion, a latch member pivotally mounted upon said bracket, a spring member normally urging said pivoted latch member toward said recesses, said latch member being provided with a recess adapted to be engaged by said spring to latch the same in inoperative position when said latch member engages the upper shoulder of said plate and being released from engagement with said recess when said latch member engages the lower shoulder of said plate, and link means connecting said brackets and preventing movement of said cushion member beyond said upper position wherein said spring engages said latch member to lock it in inoperative position.
2. In a seat structure, a cushion, a back equipped with a plate having a plurality of spaced recesses therein and a pair of side flanges, guide links carried by said side flanges and each provided with an arcuate slot, a bracket carried at the back portion of said cushion, a guide pin carried by said cushion bracket and engaging the slots of said guide links, said cushion bracket being equipped with a pivotally-mounted latch member and with nose-equipped spring means engaging said latch member, and shoulders at the top and bottom of said plate, said latch member being provided with a recess adapted to be engaged by the nose of said spring whereby when said latch member engages the upper shoulder said spring engages said recess to lock the same in inoperative position and when said latch member engages the lower shoulder to release said spring to render said latch member operative.
